UNITED STATES PATENT OFFICE.

ELIAS HANKINS, OF STREETMAN, TEXAS.

PLOW.

1,128,604.

Specification of Letters Patent.

Patented Feb. 16, 1915.

Application filed December 18, 1912, Serial No. 737,526. Renewed July 24, 1914. Serial No. 852,932.

To all whom it may concern:

Be it known that I, ELIAS HANKINS, a citizen of the United States, residing at Streetman, in the county of Freestone and State of Texas, have invented certain new and useful Improvements in Plows, of which the following is a specification.

This invention relates to plows and comprehends an improvement over my Patent 10 No. 709,901.

The primary object of the invention is to provide a plow including a novelly adjusted stock and an adjustable colter knife, said stock being composed of two angular 15 side bars connected in spaced relationship and having a flanged block secured between their upper ends.

The invention also aims to provide a plow of this nature, which shall be of extremely 20 simple construction, cheap to manufacture, strong, durable, and capable of quick and easy adjustment.

With these and other objects in view, as will become more apparent as the description 25 proceeds, the invention consists in certain novel features of construction, combination, and arrangement of parts, as will be hereinafter described and claimed.

For a complete understanding of my invention, reference is to be had to the following description and accompanying drawings, in which,

Figure 1 is a side elevation of my improved plow, Fig. 2 is a similar view, partly 35 in section, Fig. 3 is a fragmentary elevation, partly broken away, showing the connection between the stock and landside, Fig. 4 is a sectional view taken upon the plane of line 4-4 of Fig. 2, and, Fig. 5 is a top plan 40 view of my invention with the plow proper removed.

Referring in detail to the drawing by numeral, 1 designates the plow beam having the curved lower end 2, which is provided 45 at its extremity with the rearwardly projecting portion 3. A pair of handles 4 are connected at their lower ends by means of the fastener 5, to the lower end of the curved portion 2 and are braced by the bars 6.

50 A landside, comprising a plate 7 reduced as at 8, and extended upwardly, as at 9, is rigidly secured to the beam 1, by means of the fastener 10 and screw bolt 11, said last mentioned bolt extending through an opening formed in the off-set portion 3 and having a nut 12 threaded upon its extremity. A

plate 13 is secured to the portion 3 of the beam 1 upon the opposite side from the landside, by means of the bolt 11 and nut 12, and extends rearwardly a short distance in 60 spaced relationship to said landside. A screw bolt 14 and nut 15 secure the inner end of said plate 13 to the landside 7. A colter knife 16 extends between the landside 7 and the plate 13 and may be clamped 65 against movement by tightening the nut 15. It will be seen that this manner of connecting the colter knife permits of the same being longitudinally connected and also permits the use of a colter knife of a relatively 70 long length. I consider this one of the primary features of my improvement because my colter knife will last for a number of years, whereas those now in use seldom last more than one year.

A plow stock, generally designated 17, and comprising the angular side bars 18, is pivotally connected adjacent one end to the upturned end 9 of the landside, by means of the bolt 19, which may be run through 80 the opening 19'. A spacing block 20 is rigidly secured between the side bars 18 by means of the fasteners 21 and serves to securely hold the bars in proper spaced relationship and also serves a purpose to be 85 hereinafter stated. The upper ends of the side bars 18 are slightly off-set, as indicated at 22 and pass on opposite sides of the curved portion of the plow beam 1. A bolt 23 extends through the side bars 18 upon 90 one side of the plow beam and the bolt 24 passes through the free ends of said bars upon the opposite side of the plow beam. It will be seen that by tightening the nuts upon these bolts, that it is possible to clamp the 95 plow stock 17 tightly upon the plow beam.

To prevent the free ends of the side bars 18 bending unduly when the nut is tightened upon the bolt 24, I provide a slotted block 26 having oppositely extending flanges 27 100 formed adjacent its upper edge. The flanges 27 engage the upper edges of the plow stock and prevent a rotation of the block 26. The block 26 is somewhat thinner than the portion 2 of the plow beam so as to permit the 105 sides of the plow stock engaging the same tightly. The inner edge of the block 26, by engaging the plow beam, will assist in holding the same against movement relative to the plow stock. I consider the manner 110 in which the plow stock is adjustably connected to the plow beam and the manner in

which the block 26 operates to be important features of my improvement.

A plow point 28 is bolted to an attaching plate 29, which latter is essentially V-shaped in cross-section and carries the threaded stud 30, which projects between the side bars of the plow stock 17 and has a nut 31 threaded upon its inner end. It will be noted that the upturned end 9 of the landside 7 raises the stock 17 somewhat above the reduced portion 8 of the landside so as to permit free access to the nut 31. The block 20, by holding the side bars 18 of the stock in parallel spaced relationship, serves to prevent the plow from setting sidewise.

32 designates the mold board which is also attached to the plate 29. When an adjustment has to be made or a plow removed, the device is turned bottom upward and the bolts 23 and 24 loosened, after which the inner end of the plow stock 17 is pushed downwardly until it engages the braces 6. The angular construction of the side bars of the plow stock, permit a much greater swing than was possible in my original plow. Having moved the stock to this position, the nut 31 is easily accessible and may be removed so as to permit an interchange of plows. The bolts 23 and 24 are next tightened so as to secure the plow stock in any desired adjusted position and the plow is ready for use.

It is to be understood that while I have shown and described the preferred embodiment of my invention, I do not wish to be limited to this exact construction, combination, and arrangement of parts, but may make such changes as will fall within the spirit and scope of the invention.

Having thus described my invention, what I claim is:—

1. In a plow of the character described, a plow stock comprising angular side bars connected in spaced relationship and extending upon opposite sides of the plow beam, a bolt passing through the ends of said side bars and adapted to clamp the same against the plow beam, and a slotted block mounted on said bolt for engagement with the plow beam to hold the latter against movement relative to the stock, the block being provided along one edge with oppositely extending flanges.

2. In a plow of the character described, the combination with a curved beam, of a pivoted plow stock including angular side bars extending on opposite sides of the beam, a bolt extending through said side bars adjacent one of their ends, a nut threaded upon the extremity of the bolt, whereby the side bars may be clamped against the beam, and a slotted block mounted on said bolt between the side bars, the block being thinner than the beam and provided along its upper edge with oppositely extending flanges engaging the upper edges of the side bars, the forward end of the block being held in engagement with the beam when the nut is tightened whereby the stock is locked against movement relative to the beam.

In testimony whereof I affix my signature in presence of two witnesses.

ELIAS HANKINS.
